DESIGN.

C. D. KELLER.

WINDSHIELD.

APPLICATION FILED MAR. 1, 1920.

55,618.

Patented July 6, 1920.

Inventor:
Clarence D. Keller

by *his Attorney.*

UNITED STATES PATENT OFFICE.

CLARENCE D. KELLER, OF LOS ANGELES, CALIFORNIA.

DESIGN FOR A WINDSHIELD.

55,618.

Specification for Design.

Patented July 6, 1920.

Application filed March 1, 1920. Serial No. 362,560. Term of patent 7 years.

To all whom it may concern:

Be it known that I, CLARENCE D. KELLER, a citizen of the United States, residing at Los Angeles, in the county of Los Angeles, State of California, have invented a new, original, and ornamental Design for a Windshield, of which the following is a specification, reference being had to the accompanying drawing, forming part thereof.

The figure is a perspective view of a windshield, showing my new design.

I claim:

The ornamental design for a windshield, as shown.

CLARENCE D. KELLER.
